SEWER CLEANER

Karl J. Kollmann, 540 Evans St., Erie, Pa.

Filed Jan. 26, 1956, Ser. No. 561,457

8 Claims. (Cl. 15—104.3)

This invention relates to sewer cleaning machines.

Machines for rotating sewer snakes made according to previous designs are cumbersome and very difficult to transport and to use. Further, sewer machines made according to prior designs do not provide means for properly disengaging the driving means from the cable and for stopping the rotation of the cable when the cable tends to snarl or to twist.

It is, accordingly, an object of this invention to provide a sewer cleaning machine which overcomes the difficulties encountered in previous machines and, more particularly, it is an object of this invention to provide a machine which is simple in construction, economical to manufacture, and simple and efficient to use.

Another object of the invention is to provide a sewer cleaning machine wherein the motor drive can be rapidly disconnected from the snake and a braking mechanism on the machine can be applied to the snake to stop its rotation.

With the above and other objects in view, the present invention consists of the combination and arrangement of parts hereinafter more fully described, illustrated in the accompanying drawings and more particularly pointed out in the appended claims, it being understood that changes may be made in the form, size, proportions, and minor details of construction without departing from the spirit or sacrificing any of the advantages of the invention.

In the drawings:

Fig. 1 is an isometric view of a sewer cleaning machine according to the invention;

Fig. 2 is a side view of the sewer cleaning machine showing parts thereof partly in longitudinal cross section with the forward split end of the snake guide broken away for better illustration of the chuck parts;

Fig. 3 is an enlarged longitudinal cross sectional view of the snake container mechanism of the device; and

Fig. 4 is a perspective view similar to Fig. 1 taken from another point.

Now with more specific reference to the drawings, a sewer cleaning machine 10 is shown having a housing 11 with a motor 14 attached thereto. The motor 14 has an end shield 13 which attaches to a flange 12 on the housing 11. A shaft 22 has a bevelled gear 21 fixed thereto by a set screw 23 which rotates the bevel gear 21 having teeth which in turn drive a ring gear 19 which is attached to a sleeve 18 by a set screw 20. The sleeve 18 is carried by a bearing 17 which is supported in a boss 15 inside the housing 11. A grease fitting 139 is provided to lubricate the sleeve 18. The sleeve 18 terminates at the inner end in a threaded portion 24 which is adapted to threadably engage a nut 25 which has a bore having an outwardly flaring portion 26 on the inner end adapted to engage a complementary sloping surface on clamping jaws 27. The clamping jaws 27 are made in three segments which are disposed to form a hollow split member tapering inwardly at each end at 26 and 37. The member 27 has a helical spring 128 which

2

urges it out of engagement with a tubular spindle or snake guide 53 when it passes therethrough.

A sleeve 28 is rotatably supported on a bearing 30 and the bearing 30 is carried in a non-rotatable sleeve 29 which is free to slide axially and has rack teeth 31 on the lower edge thereof. The rack teeth 31 are engaged by a gear 32 which freely rotates in a bore in a boss 33 and is operated by the handle on the machine 10. When the gear 32 is rotated in a counterclockwise direction, the outwardly flared surface 35 of the sleeve 28 engages a surface 37 on the clamping jaws 27 and urges the clamping jaws 27 into engagement with the tapered surface 26. Since the clamping jaws 27 are restrained from forward motion by the nut 25, they are squeezed together, thereby forming a lock and clamping it down on the spindle 53. The spindle 53 is in turn slotted at the end at 137 defining two end segments so that the end thereof will be squeezed and, therefore, close on the cable or snake therein and it clamps the cable which is contained in a container 131 to rotate the container 131 and the cable therein. If a snake having the same diameter as the outside diameter of the end 137 of the spindle 53 is inserted instead of the container 131 and small snake, the clamping jaws 27 will clamp directly on the snake and spin it.

The container 131 is made of thin sheet metal and has the spindle 53 attached thereto at 38 by means of rivets 39. The spindle 53 is carried in a block 55 by means of a bearing 6 and is freely rotatable therein.

A collar 69 is fixed to the spindle 53 and rotates therewith. The block 55 has an overhanging lug 64 which overlies a cylindrical extension 63 on the housing 11 which is received therein at 62. The snake may be made of a helically twisted wire and is preferably curled up around an inner surface 42 and the end thereof extends through the hollow spindle 53 and out through the front end at 43 so it may be pulled out freely when the lever attached to the gear 32 is disengaged.

The entire container 131 and the block 55 may be removed by lifting a pin 45, thereby pulling an end 46 thereof out of the hole in the extension 63. The container 131 with the hollow spindle 53 may then be pulled out away from the motor 14 and casing with the cable and a larger sized cable having the approximate outside diameter equal to the outside diameter of the spindle 53 may be substituted therefor so that the machine has the dual purpose of handling a small cable or snake in the container 131 through the spindle 53 or handling a large sized cable or snake alone.

In operation, the operator will put a coil of cable in the container 131 by feeding it back through the spindle 53 with the end projecting through the outer end of the spindle 53. He will then insert the spindle 53 through the opening in the sleeve 28 and put the block 55 onto the cylindrical housing extension 63 and allow the pin 45 to snap into place. He will then start the motor 14 which will start the gear 19 rotating and rotate the sleeve 18. Then with the movement of the handle to give the gear 32 a counterclockwise rotation, the sleeve 28 will be urged forward, squeezing the driver jaws 27 into engagement with the tapered surface 26 and causing the tapered jaws 27 to clamp on the outer periphery of the spindle 53 or on the snake if a large snake alone is used. The motor 14 will spin the container 131 and the snake therein to rotate the snake and thereby cause it to remove obstructions from pipes or the like. The handle can be released to allow the split jaws 27 to disengage the cable or the spindle 53 and the cable can be manually pulled forward another length to have it inserted into the pipe.

If a sudden snarl occurs in the snake, the handle can be moved in the opposite direction to rotate the gear

32 in a clockwise direction which will pull the collar 69 which is fixed to the spindle 53 back into engagement with the forward surface of the block 55, thereby applying a braking action to the spindle 53 and the drum and stopping it with the snake therein.

The foregoing specification sets forth the invention in its preferred practical forms but the structure shown is capable of modification within a range of equivalents without departing from the invention which is to be understood is broadly novel as is commensurate with the appended claims.

The embodiments of the invention in which an exclusive property or privilege is claimed are defined as follows:

1. A machine for cleaning a sewer comprising a housing, a snake engaging means disposed in said housing, a generally cylindrical shaped snake container rotatably supported on said housing, a sewer snake coiled in said container and having an end extending from the axial center of said container through said snake engaging means and from said housing, means to engage said snake engaging means to urge it into engagement with said snake, motor means to rotate said snake engaging means and a collar member fixed to said container concentric to said snake, and brake means supported on said housing comprising a member movable on said snake engaging means to selectively engage said collar member to stop said snake from rotation, said brake means and said snake engaging means being connected whereby said snake engaging means is released from said snake when said brake means is engaged.

2. The machine recited in claim 1 wherein said snake engaging means comprises a split sleeve.

3. The machine recited in claim 1 wherein said snake engaging means comprises a tubular snake guide on said container, one end of said tubular snake guide being split and adapted to be squeezed into engagement with said snake.

4. The machine recited in claim 3 wherein said collar member is attached to said snake guide.

5. In combination, a machine for rotating a sewer snake and a sewer snake comprising a housing having a tubular member rotatably supported therein, means attached to said tubular member for rotating it, one end of said tubular member being flared, a rack member non-rotatably supported in said housing in alignment with said tubular member, gear means to move said rack member toward and away from said flared end of said tubular member, a tubular snake guide attached at one end to a snake support, a snake in said support, means to rotatably support said snake guide in alignment with said tubular member with said snake extending through said tubular member and said snake guide, means to engage said snake guide to rotate it upon movement of said rack member in a first direction to bring said means for rotating said snake guide into engagement with said flared end of said tubular member, and means to stop said snake guide from rotating upon movement of said rack member in the opposite direction and means on said machine for binding said snake within said snake guide for rotating therewith.

6. The combination recited in claim 5 wherein a second tubular member is rotatably supported in a sleeve carried by said rack member and has a flared end opposed to the flared end of said first tubular member,

said second tubular member being movable with said rack member toward and away from said means for rotating said tubular snake guide, said means for rotating said tubular snake guide comprising a split sleeve having inwardly tapering ends, one engageable with said first tubular member flared end and the other engageable with that of said second tubular member, said split sleeve being urged together to clamp it on said snake guide to lock said snake to said tubular members whereby said snake is rotated with said tubular members.

7. In combination, a machine for rotating a sewer snake and a sewer snake comprising a housing having a tubular member rotatably supported therein, means attached to said tubular member for rotating it, one end of said tubular member being flared, means supported on said housing in alignment with said tubular member, means to move said means on said housing toward and away from said tubular member, a snake container having said snake therein and extending out through said tubular member, means to engage and rotate said snake and said container upon being moved by said means on said housing into engagement with said flared end of said tubular member, brake means on said machine to stop said snake from rotating, and means to engage said brake means upon movement of said snake engaging means and said rotating means out of engagement with said flared end of said tubular member.

8. A machine for rotating a sewer snake comprising a housing having a first and a second tubular member supported in said housing in alignment with each other, spaced from each other, and having their bores flared on opposite ends, a split sleeve between said tubular members having a bore in alignment with the bores of said tubular members, said sleeve having tapered ends engaging said flared ends and being adapted to be compressed by said tubular members, a hollow rack member non-rotatably supported and slideable axially of said tubular members in said housing rotatably supporting said second tubular member, a tubular snake guide having a split end defining two end segments concentrically disposed in said second tubular member and said split sleeve, means to move said rack member in a first direction to urge said second tubular member toward said first tubular member to compress said sleeve and force said split end segments to cause them to grip a snake, means for supporting a coiled snake on said snake guide, means on said snake guide to engage said rack member to stop rotation thereof when said rack is moved in a second direction, and means to rotate said first tubular member.
